UNITED STATES PATENT OFFICE.

JOHN P. GIBSON, OF CHICAGO, ILLINOIS.

COLLAR.

1,159,761.

Specification of Letters Patent.

Patented Nov. 9, 1915.

Application filed October 5, 1914. Serial No. 864,986.

To all whom it may concern:

Be it known that I, JOHN P. GIBSON, a citizen of the United States, residing in Chicago, in the county of Cook and State of Illinois, have invented a new and useful Improvement in Collars, of which the following is a specification.

My invention relates in general to collars for men and women, and more particularly to articles of this character constructed of linen or other cloth adapted to be laundered and starched for use, it being understood, however, that the invention has a wider application, being capable of successful embodiment in collars constructed of rubber, rubber composition, paper, and in fact any preferred or usual materials.

A principal object of the invention is to provide an article of this general character particularly adapted for use during the hot periods of the year and which, while affording the desired and necessary protection to the neck of the wearer from the coat collar, will insure comfort and freedom from the ordinary effects of summer and other high temperatures.

A further object of the invention is the provision of a collar particularly adapted for use by persons having relatively short and large necks.

I am aware that numerous collars have been devised and constructed prior to my invention which have been adapted to rest low on the neck of the wearer but these collars have all either been of uniform height at the front and back or have been of the "stand-up" type with folded-over wings in front.

My invention contemplates the provision of a folded-over collar which may be of any desired height at the rear and sides of the neck of the wearer and which will be lower in front than at these parts. As is generally well known, a collar of the usual height in front in hot weather is frequently uncomfortable by reason of the fact that in standing high in front it continually rubs against the chin and thereby causes an unpleasant feeling as well as soon becoming soiled and wilted. A collar embodying my invention eliminates this unpleasant feeling by reason of the low height which may be given the front portion of the collar, the collar being capable of construction with this low front portion and at the same time having any desired height at the sides and

rear, where there is no pressure from the neck, to prevent contact of the coat collar of the wearer with the neck. A collar constructed in accordance with my invention will, therefore, while possessing all the benefits of the collars now in use, render the wearer much more comfortable by reason of the freedom and exposure given the chin and front portion of the neck of the wearer.

A further object of the invention is the provision of a collar of the character described which may be economically manufactured and which will be pleasing in appearance and well calculated to meet with popular approval as to style.

Other objects and advantages of the invention will be apparent as it is better understood from the following description when considered in connection with the accompanying drawing illustrating a preferred embodiment thereof.

Referring to the drawing, Figure 1 is a perspective view embodying my invention; Fig. 2 is a vertical sectional view taken through the center of the collar showing a front end of it extended; and Fig. 3 is a diagrammatic view of a blank from which the collar shown in Figs. 1 and 2 may be constructed.

While on the drawing the collar shown consists of a single sheet of suitable material, it will be manifest that this and other collars embodying my invention may be made of two, three or in fact any number of plies or thicknesses of material.

In the present instance the back 4 of the collar is of the usual height given the stand-up, turn-over collars at present generally in use. This collar is composed of a single sheet of one or more plies folded over throughout its length at 5 to constitute an inside portion 6 and an outside portion 7. The inside portion at the rear is provided with the usual collar button opening or button hole 8 and at the front the ends 9 are adapted to over-lap and are provided with collar button openings or button holes 10 in accordance with the usual custom. The front of the collar, however, is much lower than the rear, being inclined from its overlapping ends 9 to points 11 located at the sides of the collar, said points being preferably so arranged as to be located well back of the chin of the wearer when the collar is in position.

In order to prevent bunching in folding

the collar to the position shown, I cut away the material beneath the points 11 to form a slot or slit 12 extending from the lower edge of the inner portion 6 to just beneath the fold at the point 11. If desired small circular holes 13 may be provided at the upper end of the slit to further insure a smooth interior.

The collar shown on the drawing may be constructed from the blank shown in Fig. 3, from which it will be noted that the blank of material consists of a single uncut portion 14 adapted to form the outer portion 7, a central portion 15 adapted to form the portion 6 between the slits 12, and an end portion 16 adapted to form the portion 6 between the ends 9 and the slits 12. It will be noted that the inside portion 6 in the present instance is adapted to fold along a substantially straight line 17 extending across the entire portion 15 and to fold also along lines 18 extending from the ends of the collar and intersecting the line 17 at its ends, the lines 18 being inclined as shown on the drawing. The slits 12 are formed at the intersections of the lines 18 and 17 so that the portions 16 may fold over on the lines 18 and the portion 15 on the line 17 whenever the collar is folded for use as in its original manufacture and as in subsequent laundering. If desired, the lower edges of the outer portion 7 may be extended downwardly at the front as seen at 19 in Fig. 2, a corresponding provision being made for this at 20 in Fig. 3.

It will be manifest that a collar embodying my invention may be cheaply constructed, as it requires little or no material more than is now needed in the construction of any of the more popular forms of turn-over collars. It may be ironed first flat and subsequently folded, as is usual in the laundering of articles of this character and with the same machinery. It will be manifest also that a collar embodying my invention extends at a sufficient height at the rear and sides to prevent contact between the neck of the wearer and the collar of the coat and

is yet sufficiently low in front to prevent rubbing of the chin on the collar, minimizing thereby the danger of soiling and wiling the collar in hot weather.

It is thought that the invention and many of its attendant advantages will be understood from the foregoing description, and it will be obvious that various changes may be made in the form, construction and arrangement of the parts without departing from the spirit and scope of the invention or sacrificing any of its material advantages, the form hereinbefore described being merely a preferred embodiment thereof.

I claim:

1. An erect turn-down or folded over collar consisting of an inner band and a continuous outer portion of substantially the same width as and parallel with the band, both adapted to extend around the neck and united along their top edges by a continuous substantially straight top bend or fold extending from side to side of the neck around the back, the front parts of said top fold being continued forward on straight lines and arranged at angles to the rear part and sloping down at said angles toward the front extremities of the collar; whereby the double back portion of the collar is of full height substantially to the sides of the neck and thence slopes downwardly on straight lines to the meeting ends of the collar.

2. A fold-over collar of even height throughout its rear portion and of decreasing height from said rear portion to the front of the collar, the outer folded-over portion of the collar presenting a substantially smooth, imperforate and unbroken vertical surface, the material of the inner portion being cut away beneath the fold at the ends of said rear portion to prevent bunching of the material.

JOHN P. GIBSON.
